United States Patent Office.

S. M. COLBURN, OF ANSONIA, CONNECTICUT, ASSIGNOR TO HIMSELF AND
SYLVESTER COLBURN, OF THE SAME PLACE.

Letters Patent No. 64,844, dated May 21, 1867.

IMPROVEMENT IN STEAM GENERATORS.

The Schedule referred to in these Letters Patent and making part of the same.

TO ALL WHOM IT MAY CONCERN:

Be it known that I, S. M. COLBURN, of Ansonia, in the county of New Haven, and State of Connecticut, have invented a new Improvement in Steam Boilers; and I do hereby declare the following, when taken in connection with the accompanying drawings and the letters of reference marked thereon, to be a full, clear, and exact description of the same, and which said drawings constitute part of this specification, and represent, in—

Figure 1, a longitudinal central section, and in

Figure 2 a transverse section.

This invention relates to an improvement in the construction of common cylinder boilers, designed more particularly for boilers for "river boats," the object being to prevent the sediment from settling directly upon the cylinder and over the fire surface, and to afford a means for removing the sediment from the boiler by the current created by drawing the water from the boiler; and consists in a plate running longitudinally through the boiler, and located near the bottom, so as to form a chamber between the said plate and the inner surface of the boiler, and the same chamber communicating with the boiler through spaces or perforations formed at the edge of the said plate, and so that the sediment or mud would collect upon the top of the said plate.

In order to the better understanding of my invention, as well as to enable others to construct the same, I will proceed to a description, as illustrated in the accompanying drawings.

A is a horizontal boiler, of any desired form or construction. B is a plate of metal running nearly or quite the entire length of the boiler, and made crowning, as in fig. 2, for its own support, and of a width equal to about one-eighth the circumference, may be more or less, and is placed within the boiler at the bottom side and formed so as to leave openings *a* communicating from the boiler proper to the space or chamber C, below the plate B, or the plate may be perforated near its edge. D, the outlet for drawing the water off from the boiler, opens into the chamber C, as seen in fig. 1. The boiler being filled in the usual manner the space C readily fills through the openings *a*, and the sediment or mud in the water above, instead of settling directly upon the surface of the boiler, as in boilers of common construction, falls upon the upper side of the plate B, and thus leaves the surface of the boiler directly over the fire free for the full action of the fire and without injury to the boiler, as there unavoidably is where the sediment is permitted to settle directly on to the boiler. Having settled upon the plate B, whenever it is desired to remove the mud or sediment therefrom, open the draw-off D, which at once creates a strong current over the plate B and through the openings *a* in the edge of the said plate, sufficient to draw the mud or sediment from the said plate, and being drawn into the chamber C it quickly and readily passes off at the draw-off. Thus, while I form a protection against injury to the boiler from the fire, I at the same time produce a ready means for removing the mud or sediment therefrom.

I do not wish to be understood as broadly claiming removing the sediment by creating a current within the boiler, but having thus fully described my invention, what I do claim as new and useful, and desire to secure by Letters Patent, is—

The plate B, constructed and arranged within the boiler so as to form a chamber, C, communicating with the boiler by means of openings or perforations *a*, substantially as and for the purpose set forth.

S. M. COLBURN.
